(57) **CLAIM**

The ornamental design for a slim can cooler, as shown and described.

DESCRIPTION

FIG. 1 is a top isometric view of a slim can cooler showing our new design.

FIG. 2 is the view of the front or rear of the slim can cooler of FIG. 1.

FIG. 3 is the view of either side of the slim can cooler of FIG. 1.

FIG. 4 is a top view of the slim can cooler of FIG. 1.

FIG. 5 is a top isometric view of a second embodiment of a slim can cooler.

FIG. 6 is the view of the front or rear of the slim can cooler of FIG. 5.

FIG. 7 is the view of either side of the slim can cooler of FIG. 5; and,

FIG. 8 is a top view of the slim can cooler of FIG. 5. The broken lines in the drawings show portions of the slim can cooler and form no part of the claimed design.

1 Claim, 4 Drawing Sheets
